(57) **CLAIM**

The ornamental design for a turbine generator, as shown and described.

DESCRIPTION

FIG. 1 is a front perspective view of the front, left, and top sides of a turbine generator showing a new design, FIG. 2 is a rear perspective view of the rear, right, and bottom sides thereof,

FIG. 3 is a front view thereof,

FIG. 4 is a rear view thereof,

FIG. 5 is a left side view thereof,

FIG. 6 is a right side view thereof,

FIG. 7 is a top view thereof,

FIG. 8 is a bottom view thereof,

FIG. 9 is a sectional view thereof taken along line 9-9 of FIG. 5; and,

FIG. 10 is a reference view for showing use situation.

The broken lines shown represent unclaimed subject matter of turbine generator and form no part of the claimed design.
